ILLUMINATED DISPLAY

Ralph N. Henderson, Terre Haute, Ind.

Application November 30, 1932
Serial No. 645,056

3 Claims. (Cl. 40—132)

This invention relates to illuminated displays and has for the primary object, the provision of a rack or stand for supporting a plurality of grouped elements bearing labels of goods or merchandise, certain ones of which may be intermittently illuminated to attract attention to the device and provide a display which will be pleasing and attractive to the observer.

With these and other objects in view this invention consists in certain novel features of construction, combination and arrangement of parts to be hereinafter fully described and claimed.

For a complete understanding of my invention, reference is to be had to the following description and accompanying drawings, in which

Figure 1 is a front elevation illustrating an illuminated display constructed in accordance with my invention.

Figure 2 is a side elevation partly in section 20 illustrating the same.

Figure 3 is a fragmentary vertical sectional view illustrating one of the label supporting elements and the illuminating means therefor.

Figure 4 is a sectional view taken on the line 25 4—4 of Figure 3.

Figure 5 is a perspective view illustrating one of the label supporting elements.

Figure 6 is a rear elevation illustrating the stand or support partly broken away to show the 30 electrical illuminating means.

Figure 7 is a front elevation illustrating a modified form of invention.

Figure 8 is a side elevation illustrating the same.

Referring in detail to the drawings, the numeral 1 indicates a substantially triangular shaped casing, the bottom wall thereof extending beyond the front wall 2 for the purpose of providing to the casing a comparatively large 40 size base 3 so that the casing will maintain an upright position when positioned on a support. A plurality of label supporting elements 4 are stacked or arranged on the base 3 in front of the casing in pyramidal formation and each element is detachably secured to the front wall 2 of the casing by a fastener 5. The elements 4 are shaped to represent containers or cans employed for the shipment and sale of food products and similar merchandise. Each element 4 is 45 surrounded by a label advertising a particular line of goods and certain of said elements have portions of the side walls cut away to form openings 6 and 7. The openings 7 are arranged next to the front wall of the casing to permit electric lamps 8 to extend into the apertured elements 4,

the electric lamps being carried by electrical fixtures 9 secured to the front wall of the casing. The other openings 6 are closed by a transparent material 10 arranged in rear of the respective labels so that when the respective lamps are 60 illuminated the light rays thereof will indirectly illuminate the labels rendering them attractive and more easily read by an observer.

The rear wall of the casing 1 is of translucent material and may have printed or otherwise applied thereon certain advertisements. The fixtures 9 are arranged in an electric circuit and another electric circuit is provided for electric lamps 12' arranged within the casing for the purpose of illuminating the advertisement on the 65 rear panel of the casing. The circuits are connected to circuit makers and breakers 11' which are electrically connected, as shown at 11, to a common electrical output 12, the latter receiving 70 electricity from any suitable source.

Referring to my modified form of invention the casing 13 has its front wall arranged in stepped formation with rows of elements 4 positioned thereon and it is preferable that the elements decrease in size by rows for the purpose of indicating on display the different sized containers in which a certain food product or the like may be obtained. The steps of the casing 13 vary in size 80 in accordance with the rows of the elements as shown in Figure 8.

The transparent material 10 employed in certain of the elements 4 may be of any desired character and the openings 6 are of such a size so as to illuminate certain portions of labels and such portions of the labels which are the most attractive and giving the greatest information 85 as to a certain product.

While I have shown and described the preferred embodiment of my invention, it will be 90 understood that minor changes in construction, combination and arrangement of parts may be made without departing from the spirit and scope of my invention, as claimed.

Having described the invention, I claim:

1. An illuminated display comprising a stand, a plurality of label bearing elements arranged in rows and carried by one wall of the stand, the opposite wall of said stand being of translucent material and bearing an advertisement, illuminating means carried by said stand for illuminating the interior thereof and some of said elements.

2. A display device comprising a substantially triangular shaped casing, a plurality of label bearing elements removably secured upon one

wall of the casing and arranged in rows one above the other and in pyramidal formation, each of said elements representing a container and provided with openings, transparent material closing one opening of each container, and the other opening thereof receiving illuminating means of the casing.

3. A display device comprising a stand, illuminating means on the stand, a plurality of label

bearing elements of hollow formation secured to a wall of the stand in rows with said rows arranged one above the other, each of said elements representing a container and provided with openings and one opening closed by a label 80 on the container, and the other opening receiving the illuminating means on the stand.

RALPH N. HENDERSON.
